Edward B. Finch. Peekskill. New York.
Letters Patent N° 241. dated Oct 16th 1829.

The Schedule referred to in these Letters Patent and making part of the same

To all whom it may concern:

Be it known that I Edward B. Finch, of Peekskill, in the County of Westchester, and State of New York, have invented a new and beautiful design on a stove and I hereby do declare that the following is a full, clear, and exact description reference being had to the accompanying drawings forming part of this specification in which

Figures 4. 5. 6 and 7 enlarged views of the ornamental parts representing the said parts clearly.

A is the front or projecting floor plate. B. is the ash box. It has four sides, or rather front, back and two side plates: E. is an ornamental panel on the ash box - a like ornamental panel adorns each side of the fire box, making four of such panels on the stove: F. is the top plate of the ash box B: G. is an ornament on each corner of the top plate F: H. is a raised ring of the grate seat: It has a chasing I. extending around it: D.D.D. are the feet of the stove. Each panel has a raised border & K is the corner of the front plate border, and g. is the middle ornament: Figure 7. represents this border with the middle ornament in full: S represents the corner border of the ash box:
